LOOSE LEAF BINDER

Erik L. Krag, Chicago, Ill.

Application November 17, 1933, Serial No. 698,432

4 Claims. (Cl. 129—17)

This invention relates to loose-leaf binders and it has for its object, providing a very simple, inexpensive and effective binder for loose leaves so arranged that the leaves can be quickly shifted from one position on the binder to another and can be conveniently and quickly inserted in the binder or removed therefrom.

Fig. 1 is a plan view of a binder which embodies features of my invention, showing the binder in its closed position; Fig. 2 is an enlarged sectional view of the binder along the line 2—2 of Fig. 1 but with the binder open; Fig. 3 is a further enlarged fragmental view of a portion of Fig. 2; Fig. 4 is a plan view of a modified form of the binder when closed; Fig. 5 is an enlarged sectional view along the line 5—5 of Fig. 4 but with the binder open; Fig. 6 is an enlarged sectional view along the line 6—6 of Fig. 4; Fig. 7 is a plan view of a portion of Fig. 4 with parts cut away; 20 and Fig. 8 is a sectional view along the line 8—8 of Fig. 4.

The binder which I illustrate as an embodiment of my invention consists of two frame members, 10 and 11, which are hinged together, opening 25 and closing as is common with binders of this nature. Each frame member comprises two plates, 12 and 13; each plate 12 consists of the main body plate 14 and the flanges 15 and 16. The flanges 15 of the two frame members are 30 pivoted together by the pivot 17.

Means are provided for locking the two members in their closed position, that is with the flanges 15 together. These means comprise the strip 18 which is slidably mounted in one of the frame plates 14 by means of guides 9, and fixed to this strip are detents 20 and 21. These detents pass through slots 19 and 23 in the two flanges 15, and as illustrated the short detents 20 normally lock onto the left hand flange 15 when 40 the binder is closed. These slots are elongated so that the strip 18 may be pushed inwardly a sufficient distance to unlock the detents from the flange 15. When the binder is in the closed position, by pushing inwardly the strip 18 the 45 two members are unlocked and may be opened. If the strip 18 then is released a spring 22 pulls the strip back to the normal position and the detents 21 catch onto the left hand flange 15 and hold the binder in a half open position. However, if the strip 18 is again pushed inwardly the 50 detents 21 are released and the binder may be opened further, as shown in Fig. 2.

The flanges 16 are arranged to support the prong strips 25. The prongs 26 are fixed to the 55 strips 25 in any suitable manner and are passed

through openings 45 in the flanges 28 of the plates 13. These strips 25 are riveted or otherwise fixed to the respective flanges 28. A strip 30 is fixed to each flange 16. The edges of the strips 30 and the flanges 28 are arranged to slide with reference to each other as indicated, and a strip 31 is preferably fixed to each flange 28 to guide the lower edge thereof with respect to the strip 30. With this arrangement, by means of a handle 32 fixed to each member 13, preferably to the flange 28, the 10 prong strips may be slid inwardly or outwardly as far as may be desired.

The movement of each prong strip may be limited if desired by means of a pin 35 or 36 fixed to one of the base plates 14 and playing in recess 15 31 or 33 in one of the flanges 40 of the plate 13. In this case the movement provided for the left hand prongs, is materially greater than that for the right hand prongs, but this may be varied to suit the needs.

To prevent inadvertent movement of the prongs I provide a rounded boss 41, fixed to a spring 42. The boss is arranged to pass into notches 43 in one of the flanges 40. The spring is fixed to one of the plates 14. The boss, by pressing on the 25 handle 32, may be forced out of the notch in which it may be positioned, and will then pass into the next notch as the plate 13 is moved further. The notches are arranged so as to cause the prongs to be properly positioned with reference to each other and the spring 42 is strong enough to hold the prongs in position until material pressure is applied.

I prefer to fasten the inner ends of the prongs 35 to the strips 25 and to pass the prongs through openings 45 in the flanges 28; and to make the prongs more rigid, flanges 46 are bent up around the openings snugly surrounding the prongs. This provides a very rigid connection between the prongs and the supporting strips.

Indicating characters 44 are formed on one plate 14 to indicate to the operator the relative positions of the binder plates 12 and 13. As the plate 13 is forced to the left the characters are successively uncovered, and the character indicates the exact relative positions of the prongs.

In Fig. 4 modified means are shown for locking the binder members in the closed and partly open positions. These means comprise a strip 51 slidably mounted on the plate 47 by means of 50 guides 48. A detent 50, which is fixed to the operating strip 51, locks onto the plate 52 when the binder is closed. This detent operates through slots 49 and 53 in the plates 51 and 52. When the strip 51 is pushed inward sufficiently 55

the binder is unlocked, and can be opened until the detent 55 becomes effective. This detent is fixed to the plate 54, and when the binder is partly open this detent is adapted to lock onto the strip 56 which is slidably mounted with reference to the plate 57 by means of guides 58 fixed to the plate 57. As the binder opens, the detent 55 catches on the plate 56 preventing further opening of the members, but by pushing inwardly further the strip 51, a finger 60 mounted on the strip 51 strikes against the flange 61 of the strip 56 and pushes the strip inwardly until the detent 55 is released, so that the binder members may be opened so far as may be desired. The 15 detent operates in a recess 59 in the strip 56. A spring 62 normally holds the strip 51 in the locking position and the spring 63 normally holds the strip 56 in its locking position.

In this modification the prong strips 65 are 20 slidably mounted directly on the flanges 66. The lower edges of the strips 65 are guided by guides 67 fixed to or cut out from and integral with the flanges 66.

Also in this case the indicating characters are 25 formed on the flange 66, and they are uncovered as the prong strip 65 is moved inwardly by the handle 68. The strips 65, 73 and 75 are rigidly connected. The movement of the prong strips 65 is limited by the pins 69 and 70, and the respective recesses 71 and 72 in the plates 73 and 74.

I claim as my invention:

1. A loose leaf binder comprising a frame having two parts hinged together, means for locking said frame parts in their closed positions, 35 said means comprising a strip slidably mounted in one of said frame parts, a detent fixed to said strip and arranged to coact with the other frame part when the binder is in its closed position; and

means for limiting the opening of the frame parts, said latter means comprising a second detent rigidly fixed to the said other frame part, and arranged to coact with the first mentioned frame part when the binder is partly open, and means 5 responsive to the movement of said strip for rendering said latter detent inoperative.

2. A loose leaf binder comprising a frame having two parts hinged together, means for locking said frame parts in their closed positions, said means comprising a strip slidably mounted in one of said frame parts, a detent fixed to said strip and arranged to coact with the other frame part when the binder is in its closed position; and means for limiting the opening of said frame parts, said latter means comprising a second detent associated with one of said frame parts and arranged to coact with the other part when the binder is partly open, and means responsive to the movement of said strip for rendering said latter 10 detent inoperative, said last-mentioned means comprising a second strip slidably mounted in one of the frame parts and arranged to be operated by said first mentioned strip.

3. A loose leaf binder as claimed in claim 2, 25 and resilient means tending to move said strips to their normal locking positions.

4. In a loose leaf binder, two L-shaped plates nested together and slidably mounted one within the other, one branch of the outer plate having edges arranged to guide the associated branch of the other plate, position-indicating characters formed on the upper surface of one branch of the outer plate, the adjacent branch of the other plate covering the characters when the binder is 30 in its normal closed position.

ERIK L. KRAG.
